UNITED STATES PATENT OFFICE.

EMMA META UNDERHILL, OF ENGLEWOOD, NEW JERSEY.

DESIGN FOR AN ASPARAGUS-SERVER OR SIMILAR ARTICLE.

54,150.

Specification for Design.

Patented Nov. 4, 1919.

Application filed April 17, 1919. Serial No. 290,878. Term of patent 14 years.

To all whom it may concern:

Be it known that I, EMMA META UNDERHILL, a citizen of the United States, and a resident of Englewood, New Jersey, have invented a new, original, and ornamental Design for an Asparagus-Server or Similar Article, of which the following is a specification, reference being had to the accompanying drawing, forming a part thereof, in

which the single figure is a perspective of an asparagus server showing my new design.

I claim:

The ornamental design for an asparagus server or similar article, as shown.

In testimony whereof I have signed this specification.

EMMA META UNDERHILL.
